Specification of Letters Patent.

Patented Nov. 18, 1919.

Application filed February 6, 1917. Serial No. 146,976.

To all whom it may concern:

Be it known that I, OTTO SOMMER, an Austrian subject, residing at Zurich, Switzerland, have invented certain new and useful Improvements in Weirs, of which the following is a specification.

The invention relates to a dam and a movable crest (such as a drum-crest, a bear-trap-crest and the like) pivoted thereto and adapted to be operated by the water pressure of the upper level. The object of the invention is to provide in connection therewith a device constructed and arranged to be automatically controlled or regulated by the height of the upper water level and to control for its return the pressure of the upper water against the movable crest, so that the crest will be rocked accordingly, in order to automatically keep or maintain a predetermined upper water level notwithstanding the variations of its water supply.

With this end in view my invention consists in certain novel features of construction and combinations of parts as will be fully described hereinafter with reference to the accompanying sheets of drawings in which:

Figure 1 is a vertical section of the improved automatic controlling device in connection with a dam and a movable crest in hinged relation thereto, the upper water being at normal height and the crest and the device in their positions of rest;

Fig. 2 shows a similar sectional representation; the upper water having risen above normal level, the controlling device and the crest being in corresponding operative positions;

Fig. 3 shows the controlling device as indicated in Fig. 1 in a detailed view on a larger scale;

Fig. 4 is a vertical section on a still larger scale of a modified form of the controlling device; and

Fig. 5 is a similar sectional view as Fig. 4 illustrating a further modification of the controlling device.

Similar numerals of reference refer to like parts throughout the several figures.

Referring to Figs. 1-3 the controlling device comprises a cylindrical sluice-valve *a*

mounted in a well or shaft *b* and adapted to cut off, when in its lower end position an opening *c* in the bottom wall or bed *b'* of the shaft (Figs. 1 and 3). The interior of this shaft is in communication with the pressure chamber *d* of the dam *D* by a suitable channel *e* or the like. The lower portion of the crest *C* pivoted at *C'* to the dam structure, extends into the said pressure chamber *d*. Within the cylindrical sluice-valve *a* is arranged a vessel *f* extending up to above the high water level of the upper pond and being supported by a hollow foot *g* or the like in communication with the said vessel. This foot rests on the bottom of a chamber *b* underneath the shaft-bed *b'* and is at all times in communication with the upper water by means of a suitable conduit pipe *g'* (Figs. 1 and 2). The water in the vessel *f* tends therefore to rise to the same height as the level of the upper water to be controlled. Into the vessel *f* is nested a cup-shaped float *h* from the upper flange *h* of which is suspended the sluice-valve *a* by means of adjustable screw-bolts *h* or the like. As to the rest the float *h* is entirely free to rise and fall with the water in the stationary vessel *f*. The dimensions are chosen in such a manner that when the upper water is at normal height, the floating-power of the float *h* is just equal to the weight of the float together with the sluice-valve *a* and any other parts or additional weights suspended therefrom, but not shown in the drawings.

When the level of the upper water rises above the normal height, for example for the distance "*z*," the float *h* and the sluice-valve *a* likewise rise and allow water to flow off from the shaft *b* and the pressure chamber *d* through the opened passage *c* into the discharge chamber *b* in connection with the lower pond, (Fig. 2). This discharge of water causes a decrease of the pressure in the chamber *d*. Owing to the diminution in pressure on the lower portion of the crest and to the increase in pressure on the upper portion of the crest resulting therefrom, there exists a moment to cause the crest to rock or overturn. In overturning the lower portion of the crest pushes

aside the contents of the pressure chamber d , while the upper portion of the rocked crest allows the upper water to discharge over its top into the lower pond, (Fig. 2).
 5 The overturning of the crest increases, until the level of the upper water has sunk sufficiently or the sluice-valve sinking with the float accordingly, has throttled the discharge of water through the outlet passage e so far, that the overturning moment is compensated for by the again increasing water pressure acting in the pressure chamber on the lower portion of the crest. The crest remains then stationary in the corresponding overturned position, (Fig. 2).
 10 When the level of the upper water is sinking still farther, the discharge of water from the pressure chamber will likewise be throttled to a still greater extent, the water pressure in the chamber d will increase still more and finally exceed the moment acting to overturn the crest. The latter then rights itself again by rocking or turning back into the position shown in Fig. 1, while the 15 sluice-valve returns into its cutting-off position.
 20

By varying the weight of the float by means of suitable additional weights preferably to be attached to the sluice-valve, or 30 by adjusting the length of the connecting means h^3 between the float and the valve, the controlling device may be adjusted for different maximum levels of the upper water. The float h moving in the vessel f only with 35 small play, acts at the same time as a hydraulic brake, whereby the "hammering" otherwise usual with cylindrical sluice-valves is obviated.

In the modification disclosed by Figs. 4 40 and 5 a tank i of a diameter " d " is connected with or mounted upon the float h^1 of a diameter " D ", the tank being supplied through a pipe k with water from the stationary vessel f^1 , the pipe k being preferably passed 45 through the floating body h^1 , as shown in drawing. Through this pipe k is passed a small distance apart an over-fall or by-wash pipe m which is supported by a hollow form piece m^1 fastened in the bottom of the vessel f^1 and discharging into the passage c . The upper end or overfall-rim of the pipe m is at the same height as the normal level of the upper water. By applying a cap or hood n over its upper end the pipe m may 50 be made to act as an automatic siphon. The float h^1 is loaded in a similar manner as the float h (Figs. 1-3), so that its floating power at normal level of the upper water is just equal to the total weight of the parts to be 55 lifted and of the water contained in the tank i .

The mode of operation of this modified form of controlling device is as follows: When the level of the upper level is rising 60 for a certain height, for example for a dis-

tance " z " the float together with the tank i and the sluice-valve a rise for the same distance " z ". But by such rising a part of the water-ballast contained in the tank, namely a water column equal to the volume

$$\frac{\pi}{4}d^2z$$

of the cylinder is discharging through the pipe m , as the latter can discharge much 75 more water than the annular channel between the two pipes h and m is able to supply. The total weight of the raised parts will thereby be reduced for the weight of the water column

$$\frac{\pi}{4}d^2z.$$

For this reason the float with the parts attached thereto will continue to rise until 80 the reduction in weight caused by the diminution of the water-ballast has become equal to the decrease in buoyance of the float.

To the above statement applies the following arithmetical relation:

The decrease in weight of the water-ballast after the float has passed the way " x " is equal to

$$\frac{\pi}{4}d^2x.$$

The decrease in buoyancy of the float is equal to

$$\frac{\pi}{4}D^2(z-x).$$

$$\frac{\pi}{4}d^2z = \frac{\pi}{4}D^2(z-x)$$

$$x = \frac{D^2}{D^2 - d^2}z.$$

Assuming for example $D=1, 2d$, then is $x=3,275z$, that is to say, the floating sluice-valve is transmitting the variations of the water level at a ratio of 3,275 to 1. By this means it is rendered possible to control or regulate inlets and outlets of great cross sectional area, as it is necessary in great weirs.

The water-ballast in the tank i acts also as a damping means for avoiding too quick motions of the cylindrical sluice valve, as the increase and decrease of the water contents of the said tank can take place only slowly. By varying the total weight or the additional weights or by adjusting the length of the connecting screw bolts of the float the controlling devices according to the Figs. 4 and 5 may be adjusted to apply likewise to different maximum levels of the upper water.

Some times it may be desired to automatically regulate not only the outlet c but also the inlet o of the shaft b in such a manner that the water supply is throttled, when the outlet passage c opens, and vice versa. For this purpose, the sluice-valve a

(Fig. 5) is provided with a tubular slide *p* which according to its being raised or lowered by the sluice-valve or float respectively, narrows or widens the cross sectional area of 5 the water inlet *o*. The general arrangement of the sluice-valve with relation to the dam or to the pressure chamber when a crest is concerned, remains the same as shown in Figs. 1 and 2.

10 I claim:

1. The combination with a dam and a movable crest in pivoted relation thereto, of a controlling device for automatically regulating the water pressure on the crest 15 and thereby operating the latter, comprising a shaft communicating with a chamber of the dam and a separate discharge-chamber, a cylindrical sluice-valve within the said shaft and normally cutting off the communication to the discharge-chamber, a stationary cup-shaped vessel extending up to the high water level of the upper water and being 20 at all times in communication with the upper water to be regulated, and a floating-body 25 within the said vessel and connected to said sluice-valve to operate the same upon a rise of water beyond the normal in the upper pond, as and for the purpose set forth.

2. The combination with a dam and a 30 movable crest in pivoted relation thereto, of a controlling device for automatically regulating the water pressure on the crest and thereby operating the latter, comprising a shaft communicating with a chamber of the 35 dam and a separate discharge-chamber, a cylindrical sluice-valve within the said shaft and normally cutting off the communication to the discharge-chamber, a stationary cup-shaped vessel extending up to the high water 40 level of the upper water and being at all times in communication with the upper water to be regulated, and a floating-body 45 within the said vessel and connected to said sluice-valve to operate the same and a water ballast tank carried by the floating-body and provided with an overflow adapted to regulate the water ballast in accordance

with the rising and sinking of the float, as and for the purpose set forth.

3. The combination with a dam and a 50 movable crest in pivoted relation thereto, of a controlling device for automatically regulating the water pressure on the crest and thereby operating the latter, comprising a shaft communicating with a chamber of 55 the dam and a separate discharge-chamber, a cylindrical sluice-valve within the said shaft and normally cutting off the communication to the discharge-chamber, a stationary cup-shaped vessel extending up to the 60 high water level of the upper water and being at all times in communication with the upper water to be regulated, a floating-body within the said vessel and connected to said sluice-valve to operate the same, and 65 a tubular slide rigidly connected with the sluice-valve and adapted to throttle the inlet of the shaft according to the rising of the sluice-valve, as and for the purpose set forth.

4. The combination with a dam and a 70 movable crest in pivoted relation thereto, of a controlling device for automatically regulating the water pressure on the crest and thereby operating the latter, comprising a shaft communicating with a chamber of the 75 dam and a separate discharge-chamber, a cylindrical sluice-valve within the said shaft and normally cutting off the communication to the discharge chamber, a stationary cup-shaped vessel extending up to the high water 80 level of the upper water and being at all times in communication with the upper water to be regulated, and a floating-body 85 within the said vessel and connected to said sluice-valve to operate the same, a water ballast tank carried by the floating body and provided with an overflow adapted to regulate the water ballast in accordance with the rising and sinking of the float, and a tubular slide rigidly connected with the 90 sluice-valve and adapted to throttle the inlet of the shaft according to the rising of the sluice-valve, as and for the purpose set forth.

OTTO SOMMER.
